UNITED STATES PATENT OFFICE.

MAX SCHEY, OF BROOKLYN, NEW YORK.

ADJUSTABLE GRID.

1,320,497.

Specification of Letters Patent. Patented Nov. 4, 1919.

Application filed October 5, 1917. Serial No. 194,832.

To all whom it may concern:

Be it known that I, MAX SCHEY, a citizen of the United States, residing in the city of New York, borough of Brooklyn, county 5 of Kings, and State of New York, have invented a certain new and useful Improved Adjustable Grid, of which the following is a specification.

This invention is an adjustable grid for 10 use with stoves and is particularly adapted to facilitate the broiling of meats, fish, etc. The object of the invention is to provide an improved grid which may be readily adjustable as to height, *i. e.*, distance from the 15 heat, and at the same time, provide means to facilitate the mechanical movement of the grid into and out of the oven or housing in which grids are generally positioned.

The preferred form of adjustable grid of 20 this invention embodies carrier members mounted for vertical travel at the opposite sides of the oven and supporting the grid. With these carrier members coöperate means for counter-balancing the grid so 25 that vertical adjustment thereof may be more readily accomplished by the employment of relatively little power exerted through an adjusting lever associated with at least one of the carrier members. Associated with the grid is a rock-shaft for imparting sliding movement to the grid through operative connections, which rock-shaft is, in turn, actuated by a second operating lever. Through the operation of the 30 first mentioned lever the grid may be adjusted relative to the fire, while the operation of the second lever moves the grid in and out of the oven to facilitate the positioning of the meats on or removing them 35 from the grid. The parts are thus counter-balanced and operate with great ease irrespective of the weight on the grid.

Features of the invention, other than those specified, will be apparent from the 40 following detailed description, when read in conjunction with the accompanying drawings.

In the accompanying drawings, I have 45 illustrated one practical embodiment of the present invention, but the construction therein shown is to be understood as illustrative, only, and not as defining the limits of the present invention.

Figure 1 is an isometric view of a grid 50 embodying the present invention, the grid being here shown within an oven, as usual.

Fig. 2 is a perspective view looking from the front of the oven the grid being removed.

Fig. 3 is an isometric view illustrating the 60 mounting of the grid for sliding movement, and

Fig. 4 is a section on the line 4—4 of Fig. 3.

Referring to the drawings, A indicates a 65 grid positioned within an oven B. The grid is of the usual form and embodies a four sided frame *a* across the interior of which extend grid bars *a'*. The grid is provided, at its opposite side edges, with rollers *c* adapted to travel in tracks C, as shown best in Fig. 3. Keepers *c'* are secured to the under side of the track C and extend upwardly and over the upper edge of frame *a* to preclude the rollers from leaving the 70 tracks while allowing of the grid to be moved back and forth on said tracks.

The tracks C are positioned at the opposite sides of the oven, interiorly thereof, and are supported from underneath by suspension rods D which extend transversely through the oven and through vertical slots in the walls thereof. The opposite ends of 75 said suspension rods D are tied together by bars E, as shown best in Fig. 1.

Secured on the exterior sides of the oven are a pair of vertical guides F between which travel rollers *f*, which are mounted on the bars E. Extending across the back of the oven is a rock-shaft G, to the opposite ends of which is secured a pair of sustaining levers *g* *g'*. These levers extend 80 forwardly exteriorly of the sides of the oven and are connected with the bars E by links *g*². The sustaining lever *g* extends forwardly only as far as the link *g*², whereas the sustaining lever *g'* is extended forwardly beyond the front edge of the oven 85 to provide an operating handle *g*³ for oscillating levers *g* and *g'* with the rock-shaft 90 100 G, as a fulcrum.

It will thus appear that the levers *g* and *g'* are connected through links *g*² and bars E with the supporting rods D by which the grid is carried, and it follows that if said 105 levers are swung upwardly the grid will be raised while, if the levers are swung downwardly, the grid will be depressed. During this vertical travel of the grid, the supporting rods D travel in the slots *d* of the 110 side walls of the oven. It is for the purpose of imparting this movement to the

grid that lever g' is made to project beyond the front of the oven so that, when the chef desires to raise or lower the grid, this result may be accomplished by operating the extension of said lever g' . In order that minimum power may be employed in the manipulation of the grid, as described, a plurality of weights H are connected with the upper ends of the links g^2 by means of chains or cables h which run over direction rollers h' . The weights H counter-balance the grid and minimize the force required for raising or lowering the same.

If the connection specified was all that was employed in the vertical manipulation of the grid, said grid would be apt to tilt if the weight was not perfectly distributed thereover and, as this distribution of weight seldom occurs, means is provided for obviating the tilting under all circumstances. This means is in the form of two steadyng rollers i which travel between the guides F and are rigidly supported relative to the bars E by crossed struts I secured at their point of crossing by rivets i' , and also secured at their opposite ends to the bars E , as at i^2 .

By this construction rocking of the bars E on the lower ends of the links g^2 is entirely obviated, since it will appear that struts I , rollers i and f , and bars E , collectively, form carrier members for the supporting rods D , one of which carrier members is mounted on each side of the oven and is actuated, in its vertical travel, between the guides F . All fear of rocking of the grid within the oven is thus entirely obviated and the grid may be raised or lowered at will by the manipulation of the handle g^3 thus formed at the forward end of the extension of lever g' .

In order to obviate any chance of the grid becoming inadvertently depressed through the positioning of heavy broils thereon, the handle g^3 is provided with a stop j pivoted at j' and coöperating with the teeth of a rack J , mounted in any suitable manner at the front of the oven. The stop j is preferably formed to gravitate into engagement with the teeth of the rack and is adapted to be raised from said teeth when it is desired to lower the grid through the manipulation of an operating finger j^2 associated therewith. By the construction specified the grid may be raised or lowered at will and locked in any predetermined position.

In the accompanying drawings and in the interest of clearness, only the lower portion of the oven is shown, the extreme upper portion thereof being cut away. It will be understood that said extreme upper portion of the oven is formed as usual and houses the burners or embers. As both of these means of producing heat for broiling the meats on the grid are old and well known in the art, it is not thought necessary to show them in

the drawings, as they would obscure the invention without adding anything to the disclosure.

Aside from the vertical adjustment of the grid, as hereinbefore described, means is provided for mechanically moving the grid back and forth on the tracks C . This means embodies a rock-shaft K extending across a portion of the back of the oven, and exteriorly thereof. To the rock-shaft K is fixed an arm k , to the free end of which is pivoted a link k' pivotally secured to a lug k^2 formed on the grid A , as shown in Fig. 1. To the opposite end of rock-shaft K is fixed a segmental rack L which meshes with a similar rack l forming a part of an operating lever l' pivoted for oscillation at l^2 . The lever l' extends forwardly to a point beyond the front of the oven and into a convenient position wherein its free end may be grasped for the purpose of operating the lever. When the lever l' is depressed, it operates through the segmental racks l and L to oscillate the rock-shaft K and throw the arm k rearwardly. This movement of the arm k draws the link k' after it and moves the grid from the position of Fig. 1, wherein it projects beyond the front of the oven, to a position wherein it is entirely within the oven. When the lever l' is elevated the grid is again moved, through the connections described, to the position shown in Fig. 1. In this manner the grid may be rolled back and forth on the tracks C from the exterior position shown, and wherein the broils may be readily positioned upon said grid, to a position within the oven to place the broils directly beneath the fire.

It thus appears that the present invention allows of two distinct adjustments; firstly, the forward adjustment of the grid relative to the fire, and, secondly, the sliding adjustment of the grid into and out of the oven. Both of these adjustments may be accomplished with ease by simply manipulating the operating levers g' and l' .

In the foregoing preferred embodiment of the invention a structure has been described which is particularly adapted for use with a gas stove but the present invention may be readily adapted for use with coal stoves, and may form a part of a broiling stove or an element of a complete range. In adapting the invention to its various environments, structural changes may be made without departing from the spirit of the invention, which is to be understood as broadly novel as is commensurate with the appended claims.

Having thus fully described the invention what I claim as new, and desire to secure by Letters Patent, is:

1. A device of the class described embodying an oven, a plurality of supporting rods extending transversely of the oven, means

associated with said rods and coöperating with guides on the oven to mount said rods for simultaneous vertical movement and to maintain both of said rods uniformly at the same level with respect to one another, horizontal guide-ways mounted on the rods within the oven and a grid mounted for sliding movement on said guide-ways, in combination with means for vertically counter-balancing the grid, a rock-shaft extending transversely of the oven, levers on the rock-shaft associated with the oposite ends of the rods and means for oscillating the rock-shaft to bodily raise and lower the rods and grid, a second rock-shaft extending transversely of the oven and having an arm thereon linked to the grid, and a lever geared to the second rock-shaft for oscillating the same, for the purpose of sliding the grid into and out of the oven, whereby the grid may be raised and lowered without effecting appreciable sliding movement thereof, and may be slid into and out of the oven without effecting vertical movement thereof.

2. A device of the class described embodying an oven, a carrier member extending horizontally across the oven and provided with horizontal guide-ways, a grid mounted for sliding movement on the guide-ways, a lever, one end of which projects into accessible position, operative connections between the lever and the grid for sliding the grid horizontally on its guide-ways, a second lever extending into accessible position, a rock-shaft operated by said lever, means operated by the oscillation of the rock-shaft for bodily raising and lowering the carrier to lift or depress the grid and means for counter-balancing the weight of the grid and carrier member, said grid being adapted for sliding movement without effecting vertical

movement thereof, and for vertical movement without effecting appreciable sliding movement thereof.

3. A device of the class described embodying an oven, a carrier member mounted for vertical movement within said oven, and provided with horizontal guide-ways for slidably supporting a grid, a grid associated with said guide-ways, means associated with the carrier member for maintaining it at all times in horizontal position to preclude tilting of the grid, a pair of operating levers extending into accessible positions, operating connections between one of said levers and the grid for imparting sliding movement to the grid when the lever is operated without effecting vertical movement of the grid, and operative connections between the other lever and the carrier member for effecting vertical movement of the grid when the lever is operated without appreciable sliding movement thereof.

4. In a device of the class described embodying an oven, a plurality of grid supporting tracks positioned within the oven, means for simultaneously raising and lowering both of said tracks while maintaining them in parallel horizontal position with respect to one another at all times, a grid slidably mounted on said tracks, an operating member positioned exterior and removable from the heated area thereof, and operative connections between the operating member and the rear end of the grid for sliding the grid longitudinally of the tracks, whereby said operating member remains cool and the operating connections are out of the path of charging or discharging of the grid.

In testimony whereof I have signed my name to this specification.

MAX SCHEY.
